UNITED STATES PATENT OFFICE.

PAUL SCHIEFER AND ERNEST SCHIEFER, OF SAN DIEGO, CALIFORNIA.

DESK ATTACHMENT FOR CHAIRS.

Application filed June 14, 1921. Serial No. 477,581.

To all whom it may concern:

Be it known that we, PAUL SCHIEFER and ERNEST SCHIEFER, citizens of the United States, residing at San Diego, in the county 5 of San Diego and State of California, have invented a certain new and useful Desk Attachment for Chairs, of which the following is a specification.

Our invention relates to desk attachments 10 for chairs whereby an ordinary chair may be converted into a student's chair and the objects of our invention are; first, to provide an attachment of this class which may be readily used in connection with an ordinary 15 chair for producing a portable student's chair; second, to provide a device of this class in which the desk may be raised and lowered to a suitable height relatively to the seat of the chair; third, to provide a device 20 of this class whereby the desk may be moved forwardly or backwardly relative to the chair; fourth, to provide a device of this class whereby the desk may be tilted to varying 25 positions relatively to the chair seat; fifth, to provide a novelly constructed attachment to be used in connection with a chair for supporting a desk and sixth, to provide a device of this class which is very 30 simple and economical of construction, durable, easy to install in position on ordinary makes of chairs.

With these and other objects in view as will appear hereinafter, our invention consists of certain novel features of construction, 35 combination and arrangement of parts and portions as will be hereinafter described in detail and particularly set forth in the appended claims reference being had to the accompanying drawings and to the characters of reference thereon which form a 40 part of this application in which:

Figure 1 is a side elevational view of a conventional chair shown in dotted lines and showing our attachment in position thereon 45 in solid lines, and showing by dotted lines a varying tilted position of the desk. Fig. 2 is a front elevational view of the chair shown in dotted lines and showing our desk secured in position thereon in solid lines. Fig. 3 is a top or plan view of the chair in dotted lines and the desk removed to facilitate the illustration and showing the remainder of the attachment, and Fig. 4 is a 50 plan or top view of the attachment with the desk in position.

Similar characters of reference refer to

similar parts and portions throughout the several views of the drawings. The supporting member 1, bracket 2, upright 3, shiftable bracket 4, pivotal bracket 5, desk 60 supporting rod 6 and desk 7, constitute the principal parts and portions of our attachment for chairs. The supporting member 1 is shaped as shown best in Fig. 1 of the drawing preferably composed of a flat board 65 approximately one inch thick, and provided with a downwardly extending leg portion 1^a. It is rigidly secured to the right front leg of the chair by means of screws 1^b, in such position that the lower end of the leg 70 member 1^a is in alinement with the lower ends of the chair leg. Secured to this supporting member 1 is a metallic bracket 2 which is triangular in form with an offset portion to extend around the leg of the chair 75 and is secured to one of the cross pieces of the chair by means of wood screws. It will be noted that it is provided with a curved web portion 2^a for strengthening the same. Secured to the front and back edges of the 80 member 1 at the upper portion are the uprights 3 by means of wood screws 3^a and their upper ends extend upwardly considerably above the upper surface of the chair. These uprights 3 are provided with elongated holes 3^b, in which are mounted thumb screws 3^c, the inner ends of which are screwed into the extended portion 4^a of the bracket member 4, thus providing means for 85 raising or lowering the bracket member 4 relatively to the uprights 3 and holding it 90 in any adjusted position thereon. This bracket 4, it will be noted, is provided with an inwardly extending ledge portion 4^b on the inner side, which is adapted for the 95 bracket 7^a to rest against when the desk is down in the position as shown in Fig. 2 of the drawings. On the opposite side of this bracket 4 from the ledge is pivotally mounted the member 5 by means of a bolt 5^a. This 100 member 5 is a U-shaped member and is provided with elongated holes 5^b therein which are positioned on an arc from the bolt 5^a and in which are mounted thumb screws 5^c which screw into the member 4 for holding the 105 member 5 in certain position on the member 4 but permitting its pivotal movement relatively thereto. The upper ends of this member 5 are provided with enlarged portions 5^d which are provided with holes 110 adapted for the rod 6 so that the rod 6 may be moved longitudinally therein. This rod

6 is secured to the desk 7 at one side, and the desk 7 is positioned so that it overhangs this rod 6 at one end and the opposite end extends a considerable distance to approximately the other side of the chair seat when positioned on the chair. It will be noted that the desk 7 is slightly pivotal upon the rod 6 so that the brace member 7^a will not engage the portion 4^b when it is desired to shift the desk relatively to the support 5, but when the member 7^a rests against the portion 4^b the frictional engagement will prevent its easy shifting.

Though we have shown and described a particular construction, combination and arrangement of parts and portions, we do not wish to be limited to this particular construction, combination and arrangement, but desire to include in the purview of our invention the construction, combination and arrangement substantially as set forth in the appended claims.

It is obvious that with this construction there is provided an attachment to be used in connection with the conventional chair, which may be readily secured to said chair, that provides an additional support on one side, that the device is adjustable so that the desk may be raised and lowered relatively to the chair seat, that the desk may be shifted forwardly or backwardly relatively to the chair, that the desk may be tilted upon the pivotal support so that it assumes varying tilted positions as desired, that the attachment is made more secure by reason of the brace 2 which connects with said support some distance from the chair and to the cross bar on the front side of the chair, that the attachment is applicable for connection with various types of conventional chairs now in use and that the device itself is cheap and economical of construction, durable, easy to operate, easy to adjust and efficient in its action.

Having thus described our invention what we claim as new and desire to secure by Letters Patent, is—

1. A desk attachment for chairs, including a supporting member adapted to be secured to one corner of the conventional chair and extend forwardly therefrom, uprights fixedly secured thereto with their upper ends extending above the supporting member, a non-tiltable vertically shiftable bracket member mounted between said uprights, means for holding said bracket in various

vertically shifted positions, a quadrant member pivotally mounted on said shiftable bracket and provided with upwardly extending lugs, a desk supporting rod shiftably and revolvably mounted in said lugs and a desk member secured to said rod and provided with a single downwardly extending bracket portion positioned to butt against and frictionally engage the inner side of said shiftably mounted bracket.

2. A desk attachment for chairs, including a supporting member adapted to be secured to one corner of the conventional straight chair and extend forwardly therefrom, channel uprights secured thereto with their upper ends extending above the supporting member, a bracket shiftably mounted between said uprights above said supporting member, thumb screw and nut means for holding said bracket in varying shifted positions, a quadrant member mounted on said bracket provided with upwardly extending lugs, means for securing said quadrant member in various shifted positions, a desk supporting rod shiftably and revolvably mounted in said lugs, a desk member provided with downwardly extending lugs secured to the ends of said rod and a bracket member secured to the under side of said desk member adapted to butt against and frictionally engage the inner side of said shiftably mounted bracket.

3. A desk attachment for chairs, including a supporting member adapted to be secured to one corner of the conventional straight chair and extend forwardly therefrom, channel uprights fixedly secured thereto with their upper ends extending above the supporting member, a non-tiltable and vertically shiftable bracket member mounted between said uprights above said supporting member, a quadrant member provided with upwardly extending lugs and pivotally mounted on said bracket, a desk member shiftably and pivotally mounted in the lugs of said quadrant member and provided with a single downwardly extending bracket portion on its underside, positioned to frictionally engage the inner side of said shiftably mounted bracket.

In testimony whereof, we have hereunto set our hands at San Diego, California this 6th day of June 1921.

PAUL SCHIEFER.
ERNEST SCHIEFER.
